UNITED STATES PATENT OFFICE.

WILLIAM SMITH HORRY AND EDGAR F. PRICE, OF NIAGARA FALLS, NEW YORK, ASSIGNORS TO UNION CARBIDE COMPANY, OF NIAGARA FALLS, NEW YORK, A CORPORATION OF VIRGINIA.

ELECTRIC FURNACE.

SPECIFICATION forming part of Letters Patent No. 757,621, dated April 19, 1904.

Application filed October 11, 1902. Serial No. 126,823. (No model.)

To all whom it may concern:

Be it known that we, WILLIAM SMITH HORRY, a subject of the King of Great Britain, and EDGAR F. PRICE, a citizen of the United States, 5 residents of Niagara Falls, in the county of Niagara and State of New York, have jointly invented a certain new and useful Electric Furnace, of which the following is a specification.

10 This invention comprises an electric furnace designed for effecting reactions at high temperatures, and more particularly for forming calcium carbid, the construction of the furnace and the arrangement of its parts being 15 such as to facilitate the tapping of the molten product of the reaction.

Calcium carbid attains a fluidity sufficient 20 to permit of tapping from the furnace only at very high temperatures, and constructions 25 whereby such necessary high temperature may be maintained in the vicinity of the tap-hole of the furnace are illustrated in the accompanying drawings, wherein—

Figure 1 is a horizontal section of one form 25 of furnace. Fig. 2 is a vertical central section of the same. Figs. 3 and 4 are modified forms shown in vertical central section. Figs. 5 and 6 illustrate further modifications in vertical central section and in horizontal section, 30 respectively. Figs. 7 and 8 show in vertical central section and in horizontal section, respectively, a form of furnace wherein the gradation in current density is effected by the arrangement of the electrodes.

35 Referring to the figures, the furnace comprises a structure having side walls 1 and a base 2, of refractory material. The base may be provided, as shown in Figs. 3, 4, 5, with flues or openings 3 for the circulation of air 40 and with a suitable interior facing 8, of refractory composition. The electrodes 4 5 may be inserted in openings in the furnace-base, as shown in Figs. 1, 2, 3, 5, 6, or may depend from above, as illustrated in the remaining figures, or may extend through the 45 side walls. As clearly shown in Figs. 3, 4, 5, and 7, the electric circuit is completed through a conductive body 6, which may be calcium

carbid, iron, carbid of iron, or other suitable material in a molten condition or which may 50 be a conducting mixture of lime and carbon or merely broken carbon, and this body is maintained by the passage of the current at a sufficient temperature to effect the required reaction in adjacent portions of the super- 55 posed furnace charge 7. This charge will for the production of calcium carbid comprise any suitable mixture of carbon and lime.

Referring now more particularly to Figs. 1 and 2, the side walls 1 of the furnace are indicated as converging to a central contracted portion, adjacent to which is the electrode 5 and the tap-hole 9. Other electrodes 4 4 of a polarity opposite to that of the electrode 5 are placed at or near the ends of the furnace. The 60 effect of this construction is to reduce the cross-sectional area of the conductive body 6 from a maximum in the region of the electrodes 4 to a minimum at or near the central electrode 5 and to cause the current density and also the 65 energy density to be maintained at a maximum in the central portion of the conductive body 6. Said conductive body is thereby heated at this central portion to a relatively high temperature, and the product of reaction, as calcium carbid, may at this point be most readily 70 withdrawn from the furnace. The same result is accomplished if the central electrode 5, adjacent to the tap-hole, be omitted, the current passing between the electrodes 4. The 75 increased current and energy density in the contracted portion of the conductor effects such local increase in temperature as to enable the product to be readily tapped from the furnace.

In Fig. 3 a form of furnace is shown wherein the conductive body 6 converges to a central contracted portion, said convergence taking place in a vertical plane. This form of furnace may be rectangular in plan or the side 90 walls also may converge toward the central electrode, as in Fig. 1.

Fig. 4 shows a construction differing in that the central electrode is omitted, the current being conducted to and from the furnace by the 95 electrodes 4 5, situated at or near the ends of

the furnace. In this case also the highest temperature is developed in a region adjacent to the tap-hole 9. The side walls in this construction may be substantially parallel or they 5 may converge in the manner shown in Fig. 1.

Figs. 5 and 6 show modified constructions wherein the base and side walls incline toward a tap-hole located at or near one end of the furnace, so as to provide for a graduated reduction of the cross-sectional area of the conductor from end to end of the furnace. In this furnace the side walls only may converge toward the tapping end, or the side walls may be substantially parallel, the reduction in 15 cross-sectional area of the conductor being secured by the inclination of the base, or the converging side walls and inclined base may be combined in a single structure.

Figs. 7 and 8 illustrate a form of furnace 20 which may be rectangular in plan and in which the conductive body 6 may be of substantially equal cross-sectional area throughout. In this construction the current passes between a plurality of electrodes 4, connected 25 in parallel to one terminal of the source of current, and a plurality of electrodes 5, connected in parallel to the other terminal. As a result of this arrangement the maximum current passes between adjacent electrodes 30 near the center of the furnace, the quantity of current passing, and hence the current density and energy density in the conductor, being progressively increased toward the center. It will be clear that in this construction, 35 as in that shown in Figs. 1, 2, 3, and 4, the current density and the energy density attain a maximum at or near the central portion of the conductive body, and the furnace product is tapped out, as indicated at 9, at this point 40 or region of maximum temperature. It is obvious that electrodes may be arranged in this manner in a furnace having side walls converging to a central contracted portion or in a furnace of the type illustrated in Fig. 4, 45 wherein the base alone is inclined or such inclination is combined with convergence of the side walls.

While the operation specifically described is the production of carbid, the furnace is capable 50 of general application, as the formation and withdrawal of any molten furnace product.

While in the operation of the furnaces shown and described the molten product flows out through a tap-hole, and is therefore specified in the claims as withdrawn by gravity, it 55 will be understood that in some cases the movement of the molten material may be assisted by mechanical means. For example, the tap-hole must be kept clear from obstructions and 60 the flow of the carbid under the action of gravity, may be suitably facilitated or assisted.

We are aware that United States Patents Nos. 750,096 and 750,170, granted January 19, 1904, to Alfred H. Cowles, disclose processes 65 in which an electric current is passed through

a charge or pool of electrically-conductive material and in which the density of the electric current is increased within the charge or pool to provide a region of maximum current density. We make no claim to anything disclosed in these patents, our claims including features which are specifically novel. 70

We claim—

1. An electric-resistance furnace, comprising a hearth to support a charge or molten product of conductive material, three or more electrodes in contact with said charge or product and so arranged and connected to the source of electric current as to maintain a region of maximum current density in an intermediate portion of said charge or product, and means adjacent to the region of maximum current density for withdrawing the product by gravity, as set forth. 75

2. An electric-resistance furnace, comprising a hearth to support a charge or molten product of conductive material and of varying cross-section, three or more electrodes in contact with said charge or product and so arranged and connected to the source of electric current as to maintain a region of maximum current density in an intermediate portion of said charge or product, and means adjacent to the region of maximum current density for withdrawing the product by gravity, as set forth. 80 90

3. An electric-resistance furnace, comprising a hearth to support a charge or molten product of conductive material with an intermediate portion of less cross-section than its end portions, a plurality of electrodes in contact with said charge or product and so arranged and connected to the source of electric current as to maintain a region of maximum current density at said intermediate portion, and means adjacent to said intermediate portion for withdrawing a product by gravity, as set forth. 100 105

4. An electric-resistance furnace, comprising a hearth to support a charge or molten product of conductive material with an intermediate portion of less cross-section than its end portions, three or more electrodes in contact with said charge or product and so arranged and connected to the source of electric current as to maintain a region of maximum current density at said intermediate portion, and means adjacent to said intermediate portion for withdrawing a product by gravity, as set forth. 110 115

5. An electric-resistance furnace, comprising a hearth to support a charge or molten product of conductive material, and three or more electrodes arranged to pass superposed electric currents through said charge or product and to maintain therein a region of maximum current density, as set forth. 120 125

6. An electric-resistance furnace, comprising a hearth to support a charge or molten product of conductive material, three or more 130

electrodes arranged to pass superposed electric currents through said charge or product and to maintain therein a region of maximum current density, and means adjacent to the 5 region of maximum current density for withdrawing the product by gravity, as set forth.

7. An electric-resistance furnace, comprising a hearth supporting a body of a conductive carbide or carbide-forming material, and 10 three or more electrodes arranged to pass superposed currents through said body and maintain therein a region of maximum current density, as set forth.

8. An electric-resistance furnace, comprising 15 a hearth supporting a body of a conductive carbide or carbide-forming material, three or more electrodes arranged to pass superposed currents through said body and maintain therein a region of maximum current density, 20 and means adjacent to the region of maximum current density for withdrawing the product by gravity, as set forth.

9. An electric-resistance furnace, comprising a laterally-converging hearth to support a body of conductive material, electrodes arranged to maintain in said body a region of maximum current density, and means adjacent to said region of maximum current density for withdrawing a product by gravity, 25 as set forth.

10. An electric-resistance furnace, comprising a laterally-converging hearth supporting a pool of a conductive carbide or carbide-forming material, and electrodes arranged to maintain in said pool a region of maximum current 35 density, as set forth.

In testimony whereof we have hereunto signed our names in the presence of two subscribing witnesses.
